UNITED STATES PATENT OFFICE.

ADOLPH RUBIN, OF ST. LOUIS, MISSOURI, ASSIGNOR TO SIEBER PRODUCTS MFG. CO., OF ST. LOUIS, MISSOURI, A CORPORATION OF MISSOURI.

LOOSE-LEAF BINDER.

Application filed October 16, 1922. Serial No. 594,816.

To all whom it may concern:

Be it known that I, ADOLPH RUBIN, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same.

10 This invention relates to loose leaf binders of the type in which the leaves are retained in position by tapes, bands or cords that are connected to a winding shaft which is adapted to be rotated in one direction to draw the tapes taut, and thus cause the leaves to be clamped tightly between the two leaf clamping members of the binder.

One object of my invention is to provide an efficient mechanism of novel design and 20 inexpensive construction for locking the winding shaft of a loose leaf binder of the general type referred to.

Another object is to provide a loose leaf binder of novel construction that is equipped 25 with a locking means for the winding shaft which requires a special key to render it inoperative and to rotate the winding shaft in a direction to slacken the tapes. Other objects and desirable features of my 30 invention will be hereinafter pointed out.

To this end I have devised a loose leaf binder that comprises a winding shaft and a coiled spring surrounding said shaft and arranged in such a manner that it does 35 not interfere with the forward rotary movement of the shaft to tighten the tapes, but does effectively hold the winding shaft against rearward rotary movement in a direction to slacken the tapes. When it is de-

40 sired to slacken the tapes so as to remove or insert leaves in the binder, it is necessary to change the normal condition of the locking spring before the winding shaft can be turned rearwardly to slacken the tapes, and 45 in order to reduce to a minimum the liability of an unauthorized person removing leaves from the binder or inserting additional leaves, I construct the winding shaft locking mechanism in such a way that a key

of a special design is required to render it 50 inoperative and to turn the winding shaft in a direction to slacken the tapes.

Figure 1 of the drawings is an end elevational view of a loose leaf binder constructed in accordance with my invention, showing 55 the tapes of the binder tightened.

Figure 2 is a similar view, showing the tapes slackened.

Figure 3 is a top plan view of the binder, showing the tapes slackened.

Figure 4 is a detail view, illustrating a portion of the winding shaft and the locking spring that is combined with same, illustrating the locking spring in its normal operative condition.

Figure 5 is a view of the parts shown in Figure 4, illustrating the key that is used to render the locking spring inoperative and to turn the winding shaft rearwardly to slacken the tapes; and

Figure 6 is a perspective view of the winding key.

Referring to the drawings which illustrate the preferred form of my invention, A and A' designate two leaf clamping members between which leaves B are arranged. C designates tapes or bands of flexible material that pass through slots in the leaves B and D designates a winding shaft to which one end of the tapes C are connected, the opposite ends of said tapes being connected to the leaf clamping member A'. The winding shaft D is rotatably mounted in bearings on the leaf clamping member A, and means is provided for preventing an unauthorized person from rotating said winding shaft rearwardly to loosen or slacken the tapes C.

90 In the form of my invention herein illustrated the means just referred to comprises a coiled spring E surrounding the winding shaft and arranged in such a way that while it does not interfere with the forward rotary movement of the winding shaft, it does effectively hold the winding shaft against rearward rotary movement. The spring E is preferably arranged at the lower end of the winding shaft D between a shaft bear-

ing 1 on the leaf clamping member A, and an abutment on the winding shaft formed by a washer 2 that bears against a pin or stop 3 on the winding shaft. Said spring 5 E is provided at its upper end with a lateral extension 4 that bears against one side of a stop 5 formed by a portion on the leaf clamping member A that extends lengthwise of the spring E, said extension 4 being preferably rigidly connected to the stop 5 by means of a perforated lug or pressed portion 6 on the stop 5 into which the extension 4 on the spring extends, as shown more clearly in Figures 4 and 5. The spring E 10 is provided at its lower end with a lateral extension 7 which also engages the same side or face of the stop 5 that the extension 4 at the upper end of the spring engages, said extension 7 having no direct connection 15 with the stop 5. The spring E is so proportioned and arranged that when it is in its normal condition, shown in Figure 4, forward rotary movement of the winding shaft E tends to unwind or open up the 20 coils of said spring, and pressure applied to the winding shaft in a direction tending to turn it rearwardly causes said winding shaft to exert pressure on the spring E in a direction to tighten same, and thus cause 25 one or more coils of the spring to exert sufficient frictional pressure on the winding shaft to securely hold same against rearward rotary movement. This is due, of course, to the fact that the lateral extension 30 7 at the lower end of the spring E has no direct connection with the stop 5 and is arranged in engagement with said stop in such a way that the twisting strain to which said spring is subjected when the winding 35 shaft is turned forwardly tends to move said extension 7 away from the stop 5, thereby increasing the diameter of the coils of the spring E and reducing the frictional pressure of said spring on the winding shaft. 40 Any attempt to turn the winding shaft rearwardly, however, exerts pressure on the spring E in a direction tending to force the lateral extension 7 thereon tightly against the stop 5, and continued pressure on the 45 winding shaft in this direction tightens the spring and causes one or more coils of same to clamp the winding shaft tightly enough to prevent it from turning rearwardly. To state it in another way, the means that is 50 used for preventing the winding shaft from being turned in a direction to slacken the tapes of the binder, consists merely of a coiled spring E wrapped around the winding shaft in such a way and combined with 55 a stationary stop in such a manner that pressure applied to the winding shaft in a direction tending to turn it rearwardly draws one or more coils of said spring into sufficiently snug engagement with the winding shaft to securely lock the same or hold 60

it against rearward rotary movement, said spring also being preferably arranged in such a way that forward rotary movement of the winding shaft untwists or opens up the coils of the spring, and thus relieves the frictional pressure of the spring on the winding shaft. 70

A key is used for rotating the winding shaft D and in order to eliminate the possibility of an unauthorized person releasing the winding shaft and turning said shaft rearwardly to slacken the tapes, I have devised the winding shaft locking means in such a way that it can be rendered inoperative only by a winding key F of special design. The locking spring E is adapted to be rendered inoperative by changing the position of the lateral extension 7 on said spring relatively to an inclined surface or cam 8 on the leaf clamping member A that is arranged in proximity to said extension 7. In the form of my invention herein illustrated the cam 8 is arranged on the side of the stop 5 against which the extension 7 bears at a point slightly above said extension, when the spring E is in its normal operative condition, as shown in Figure 4. To render the locking spring E inoperative, said spring is compressed endwise so as to cause the extension 7 thereon to ride up onto the cam 8, and thus twists said spring in a direction to increase the diameter of the coils of same sufficiently to prevent said coils from tightening sufficiently to clamp the winding shaft D when said shaft is turned rearwardly. The winding key F is provided with a tubular portion 9 that is adapted to be slipped over the lower end of the winding shaft D, and an inclined slot 10 is formed in said tubular portion 9 so as to produce a shoulder 11 and a wedge or cam 12, as shown in Figure 6. To turn the winding shaft D forwardly so as to tighten the tapes C, the tubular portion 9 of the winding key F is slipped over the lower end of the winding shaft in such a way that the pin 3 will enter the slot 10 and said key is then turned to the right, so as to cause the shoulder 11 thereon to engage the pin 3 on the winding shaft, and thus transmit the rotary movement of the key to the winding shaft. When it is desired to render the locking spring E inoperative, the tubular portion 9 of the winding key is arranged in such a way that the pin 3 on the winding shaft is in alignment with the slot 10 in said tubular portion, and said tubular portion is then slipped upwardly over the winding shaft and turned to the left so as to cause the cam or wedge portion 12 of same to be forced between the pin 3 on the winding shaft and the washer 2 located above the same, thereby moving the washer 2 upwardly relatively to the pin 3 and causing the lateral extension 7 on the locking spring E 80 85 90 95 100 105 110 115 120 125 130

to ride up onto the cam 8, as shown in Figure 5. This, of course, causes the locking spring E to be rendered inoperative, as previously described, and thereafter the 5 winding shaft can be turned rearwardly in a direction to slacken the tapes by turning the winding key F to the left. Various means can be used to prevent the winding shaft D from moving longitudinally of its 10 bearings on the leaf clamping member A when the wedge portion 12 of the key F is forced between the pin 3 and washer 2 to compress the spring E, the means herein shown consisting of an abutment 13 on the 15 winding shaft that lies between two shaft bearings on the leaf clamping member A, as shown in Figure 3.

Having thus described my invention, what I claim as new and desire to secure by 20 Letters Patent is:

1. A loose leaf binder, comprising a winding shaft, and a coiled spring surrounding said shaft and arranged in such a way that pressure applied to said shaft in a direction 25 tending to turn it rearwardly causes one or more coils of said spring to be drawn into sufficiently snug engagement with said shaft to lock or hold same against rearward rotary movement.

30 2. A loose leaf binder, comprising a winding shaft, a coiled spring surrounding said shaft and arranged in such a way that pressure applied to said shaft in a direction tending to turn it rearwardly causes one or more 35 coils of said spring to be drawn into sufficiently snug engagement with said shaft to lock or hold same against rearward rotary movement, and means for changing the normal condition of said spring so as to render 40 it inoperative for holding said shaft when said shaft is subjected to pressure in a direction tending to turn it rearwardly.

45 3. In a loose leaf binder, a winding shaft, and a coiled spring surrounding said shaft and arranged in such a manner that it does not interfere with the forward rotary movement of said shaft but does prevent said shaft from being turned rearwardly.

50 4. In a loose leaf binder, a winding shaft, a coiled spring surrounding said shaft and arranged in such a manner that it does not interfere with the forward rotary movement of said shaft but does prevent said shaft from being turned rearwardly, and means 55 for rendering said spring inoperative when it is desired to turn said shaft rearwardly.

55 5. A loose leaf binder, comprising a winding shaft, a stop or abutment device arranged in proximity to said shaft, and a coiled 60 spring surrounding said shaft and combined with said abutment device in such a way that forward rotary movement of said shaft tends to open up the coils of said spring and pressure applied to said shaft in a direction to 65 turn it rearwardly causes one or more coils

of said spring to contract and exert sufficient frictional pressure on said shaft to hold it against rearward rotary movement.

6. A loose leaf binder, comprising a winding shaft, a stop or abutment member arranged in proximity to said shaft, a coiled spring surrounding said shaft and combined with said abutment member in such a way that it effectively holds said shaft against rearward rotary movement, and means for 70 rendering said spring inoperative when it is desired to turn the shaft rearwardly.

7. A loose leaf binder, comprising a winding shaft, a stop or abutment member arranged in proximity to said shaft, a coiled spring surrounding said shaft and combined with said abutment member in such a way that it effectively holds said shaft against rearward rotary movement, and co-operating means on said spring and abutment member that are adapted to be brought 75 into engagement with each other to render said spring inoperative when it is desired to turn said shaft rearwardly.

8. A loose leaf binder, comprising a winding shaft, a stop or abutment member arranged in proximity to said shaft, a coiled spring surrounding said shaft and provided at one end with a lateral extension that engages said abutment member, means for connecting the opposite end of said spring to said abutment member, and a portion on said abutment member that is adapted to be brought into engagement with said extension so as to relieve the pressure of said spring on 90 said shaft when it is desired to turn the shaft rearwardly.

9. A loose leaf binder, comprising a winding shaft, a coiled spring surrounding said shaft, means combined with said spring for causing one or more coils of said spring to contract and thus tightly grip the winding shaft when the winding shaft is subjected to pressure in a direction tending to turn it rearwardly, and means for rendering said 100 spring inoperative to prevent rotary movement of said shaft.

10. A loose leaf binder, comprising a winding shaft, a stop or abutment member arranged in proximity to said shaft, a coiled spring surrounding said shaft and provided at one end with an extension that bears against said abutment member, means for connecting the opposite end of said spring to said abutment member, a cam or inclined surface on said abutment member arranged in proximity to the extension on said spring, and means for causing said extension and cam surface to engage each other when it is desired to render said spring inoperative. 115

11. A loose leaf binder, comprising a winding shaft, a spring mounted on said shaft and arranged so that it clamps and holds said shaft when the shaft is subjected to pressure in a direction to turn it 120 125 130

rearwardly, an extension on said spring, a cam or inclined face that is adapted to engage said extension to render the spring inoperative for holding the shaft, and means for compressing the spring so as to cause said extension to engage said inclined surface.

12. A loose leaf binder, comprising a winding shaft, a spring surrounding said shaft

and arranged in such a way that it normally holds said shaft against rearward rotary movement, a device for exerting pressure on said spring in a direction to render it inoperative for holding said shaft, and a winding key provided with means for causing said device to engage said spring.

ADOLPH RUBIN.
